UNITED STATES PATENT OFFICE

ARNOLD E. DENTLER, OF CHICAGO, ILLINOIS, ASSIGNOR TO W. H. MINER, INC., OF CHICAGO, ILLINOIS, A CORPORATION OF DELAWARE

APPARATUS FOR TESTING DRAFT GEARS

Application filed May 2, 1927. Serial No. 188,076.

This invention relates to method of, and apparatus for, testing draft gears.

In testing draft gears for railway cars, it is common practice to use a hammer which is elevated to different heights and dropped upon a draft gear placed upon a suitable anvil so as to be struck by the hammer when it descends. It has been found that a hammer test under such conditions as these, results in inaccuracies due to the fact that in actual practice a coupler or drawbar is interposed between the front follower of the draft gear and the impacting force, the coupler in transmitting the impact having an effect thereon which heretofore has not been taken into account in testing the gears, and hence has caused the occurrence of inaccurate tests.

An object of the present invention is to provide a method of obtaining accurate results from the hammer tests, wherein a member having the characteristics of the usual coupler or drawbar is interposed between the force of impact delivered by the hammer and the draft gear which is maintained in position, approximating as closely as possible, the operation of the parts under actual conditions.

Another object of the invention resides in providing a frame for holding the draft gear and for guiding the coupler in its movements so that the blow of the hammer is transmitted through the coupler to the draft gear.

Still another object of the invention is to provide an apparatus of this character wherein the guide means for the coupler are detachably connected to a main retaining frame, which has means corresponding to draft lugs of a railway car, certain of the lugs being displaceable to permit insertion and withdrawal of the gear from the main frame when the coupler guiding means are detached therefrom.

Other and further objects of the invention will more clearly appear from the description and claims hereinafter following.

In the drawings, forming a part of this specification, Figure 1 is a fragmentary front elevational view of a drop hammer such as used in testing railway draft gears and showing my improvements used in connection

therewith. Figure 2 is a vertical, longitudinal section on line 2—2 of Figure 1 with the gear, follower and coupler shank omitted. Figure 3 is a horizontal sectional view of the invention corresponding substantially to line 3—3 of Figure 1. Figure 4 is a top plan view of the testing and guiding structure. And Figure 5 is a vertical section on line 5—5 of Figure 2 of the upper portion of the main and guide frames showing the detachable locks for holding the draft gear in position in the frame.

As shown in the drawings, 10 denotes an anvil upon which is placed the testing frame illustrated in detail in Figures 2 to 5, inclusive, and containing the gear 11 to be tested. On top of the gear 11 is usually placed a follower 12 by which the blow is transmitted from the vertically movable nine thousand (9,000) pound hammer 13. The gear 11 is supported on the usual follower 14, if of the type employing a rear follower in service, otherwise it rests directly on anvil blocks hereinafter described. The weight 13 is guided in its vertical movements by suitable heavy side guide members 15—15. The weight is lifted by suitable hoisting mechanism and dropped as desired.

The testing apparatus comprises what may be termed a main frame A and a detachable guide frame B. The main frame A includes a base plate in the form of a relatively heavy substantially rectangular plate 16 having upright channel members 17—17 rigidly secured thereto through the medium of reinforcing angle plates 18—18, the latter being fixedly secured to the base plate 16 by any suitable means, preferably rivets as shown.

Each of the upright channel members 17—17 comprises a relatively wide plate like section or web 19 having outwardly projecting flanges 20—20 at the opposite vertical side edges thereof. Anvil blocks 21—21 are provided and are directly supported on the base plate 16 and are secured to the side members 17—17 by bolts 22—22 which extend through the blocks 21—21, the channel members 17—17, and the vertical flanges of the corresponding angle members 18—18. The channel members 17—17 are spaced apart a distance

corresponding substantially to the standard spacing between the usual channel-shaped center draft sills of a railway car underframe and the anvil blocks 21—21 correspond to the usual rear stop lugs of the draft sills. The channel members 17—17 are rigidly united by the rear tie plate 23, and the front tie strap 24. The plate 23 is rigidly secured to the rear set of flanges 20—20 of the members 17—17 in any suitable manner, preferably by a series of rivets as most clearly shown in Figure 2. The tie strap 24 is in the form of an elongated rectangular bar and has its opposite ends secured to the corresponding flanges 20—20 at the forward sides of the members 17—17. The opposite ends of the tie strap 24 are preferably secured to the flanges 20—20 by bolts 25—25. It will thus be seen that the tie plate 23 is detachable upon removal of the bolts to thereby permit insertion of a draft gear through the front of the testing apparatus.

At the upper end each channel member 17 is provided with a hinge bracket plate 26 suitably secured to the corresponding web section 19 of the member 17 by means of a pair of screws. To each hinge plate 26 is hinged one of the retaining lugs 27—27, each lug being provided with a pair of hinge-eyes 28—28 adapted to accommodate a hinge bolt 29 which extends through an eye formed in the hinge plate 26, the bolts 29—29 being utilized in connecting the detachable guide frame B to the main frame A, in a manner hereinafter described. Each of the displaceable retaining lugs 27 is preferably in the form of a hook member as most clearly shown in Figure 5, the hook portion 30 of each lug being adapted to overhang the inner side of the corresponding side member and simulate the usual corresponding front stop lug of the draft rigging. In order to lock the retaining lugs 27 in operative fixed position, each member 17 is provided with a detachable retaining bolt 31 at the upper end thereof, the flanges of the member 17 being provided with openings to accommodate the bolts 31—31, and each bolt in turn being adapted to engage and bear on the outer side of the corresponding retaining lug 27. The webs 19 of the channel members 17—17 are cut out as indicated at 32 to accommodate projections upon certain types of draft gears. The frame A is complete in itself for supporting the draft gear for tests without the coupler. To insert the gear into the frame A the locking bolts 31 are removed and the retaining lugs 27—27 swung outwardly to inoperative position after which the tie plate 24 is removed and the gear entered through the front of the frame. The follower plate on which the gear is supported rests on the blocks 21—21, while the follower plate 12 is placed on top of the gear. The retaining lugs 27 are then swung inwardly to over-

hang position with reference to the follower plate 12, the tie plate replaced, and the locking bolts reinserted. When the guide frame is used in connection with the main frame A, the draft gear 11 is inserted into the frame A in the same manner above described.

The guide frame B is adapted to be detachably connected to the main frame A, the frame B being of such character that when the same is in position, it is adapted for the reception of a column or bar member corresponding in dimensions to the shank of the usual standard coupler, which member is movably guided into contact with the draft gear follower when held by the main frame. The frame B comprises channel members 33—33 which form the side walls thereof, and provide what are in effect continuations of the side walls of members 17—17 of the main frame A, the walls 33 being cut out as indicated at 330 to permit the operation of the pivoted retaining lugs 27—27, the lower ends of the members 33—33 being adapted to rest upon the top edges of the members 17—17 when the parts are in position. The members 33—33 are provided with flanges 34—34 which are connected together in spaced relations by a rear plate 35, the edges of which are secured to said flanges by rivets. The plate 35 extends downwardly beyond the lower ends of the channel members 33—33 as indicated at 36 and is adapted to rest upon the top edge of the plate 23, the edges of the extension 36 being connected to the flanges of the members 17—17 by removable bolts 37—37. The flanges 34—34 of the members 33—33 at the forward portion of the apparatus have secured thereto by means of rivets, bars 137—137, said bars terminating flush with the upper ends of the flanges 34—34, and extending downwardly below the lower ends of said members a suitable distance as indicated at 38, the extensions 38 being secured to the flanges of the members 17—17 by detachable bolts 39. The bolts 29 and 31 extend through the extension 36 on the plate 35, and the extensions 38 on the bars 137. At the front of the frame at a point spaced inwardly from the upper end thereof, is a cross bar 380, said bar being secured to the flanges 34—34 of the side members 33—33 by threaded members 39—39. At the top of the frame B at the forward side thereof is a cross bar 40 having its ends secured to the forward flanges of the members 33—33 by threaded members 141—141 as best shown in Figure 4. The intermediate portions of the bars 380 and 40 are inwardly offset as best shown in Figures 3 and 4, and to the lower bar 380 at an intermediate point, on its inner surface, is a channel-shaped guide member 41, and oppositely disposed to the guide member 41 is a channel member 42 of a similar character which is secured to the plate 35 as best

shown in Figure 3. The upper bar 40 is provided with a channel-shaped member 43 having its flanges inwardly disposed, this member having its flanges spaced apart a greater distance than those of members 41 and 42, the member 43 being secured to the inner surface of the bar 40 by means of rivets. An oppositely disposed guide member 44 similar to the member 43 is secured to the plate 35 by rivets, the members 41—42, 43 and 44, being adapted to provide guide means for a column or bar member 45 corresponding to the usual standard coupler shank, which member is interposed between the drop hammer 13 and the follower 12 of the draft gear. The frame B is readily detachable and attachable by removal or application of the bolts 37—39, 29 and 31.

As above stated, heretofore it has been customary in testing draft gears to drop the hammer 13 directly upon the front follower 12 of the draft gear, but tests of this kind under certain conditions, do not produce entirely accurate results, for the reason that the tests are not made under conditions similar to actual practice. In actual practice a drawbar is interposed between the impacting force from an adjacent car which force is transmitted by the coupler to the draft gear, and due to factors such as the resiliency or compressibility of the coupler and other factors, a test wherein the hammer is dropped directly upon the follower of the gear is rendered inaccurate for said purposes.

This invention therefore contemplates a method consisting in buttressing a draft gear against a stationary member such as anvil 10, holding the draft gear under conditions approximating actual practice, in the manner disclosed by the frame A, directing an impacting force toward the gear through the medium of a weight such as the hammer 13, interposing a column or bar member 45 corresponding in dimensions to and having the physical characteristics of the usual standard coupler shank, between the impacting force represented by the hammer 13, and the draft gear, and guiding the column or bar member in such manner as to effect transmission of the impacting force to the gear under conditions approximating actual practice, thereby subjecting the column to compression forces and giving an indication as to the performance of the draft gear, the frame B being shown in the drawings for accomplishing this purpose.

While I have herein shown and described what I consider the preferred manner of carrying out the invention, the same is merely illustrative, and I contemplate all changes and modifications which come within the scope of the claims appended hereto.

I claim:

1. In a testing apparatus, the combination with a frame provided with a base and side

members adapted to accommodate a draft gear and spaced abutments carried by each of said side members corresponding to the front and rear stop lugs of a draft rigging; of a metal column member having the physical characteristics of the usual standard coupler; and means co-operating with said column member for guiding the same into bearing relation with said draft gear to transmit an impacting force thereto. 75

2. In a testing apparatus, the combination with a main frame adapted for the reception of a draft gear, said frame being provided with abutment elements corresponding to the usual front and rear sets of stop lugs of a draft rigging, one of said sets of abutment elements being displaceable to permit insertion of a draft gear in the frame; means for locking the displaceable elements in fixed position; and a second frame detachably connected to said first frame and provided with guide means for the slidable reception of a metal column member having the physical characteristics of the usual standard coupler, whereby a blow upon said column member 90 will be transmitted to the draft gear held in said main frame.

3. In a testing frame, the combination with spaced side members; of means rigidly connecting said members, including a detachable strap at one side; abutment elements at opposite ends of each of said members, said abutment elements corresponding to the front and rear stop lugs of a railway draft rigging; a second frame super-positioned with respect to said first frame and rigidly connected with the latter, said second frame being provided with means for guiding a metal column member having the physical characteristics of the usual standard coupler into contact with said draft gear while disposed in said first frame. 100 105

4. In a testing apparatus of the character described, the combination with a frame adapted for the detachable reception of a draft gear; and a second frame comprising side members, and means for detachably connecting said side members together; extensions on said second frame detachably connected to said first frame; and guide means on said second frame adapted for the slid- 110 115 able reception of a metal column member having the physical characteristics of the usual standard coupler adapted to engage the draft gear in said first frame.

5. In a testing apparatus of the character described, the combination with a frame adapted for the detachable reception of a draft gear; and a second frame comprising side members, and means for detachably connecting said side members together; extensions on said second frame detachably connected to said first frame; and guide means on said second frame adapted for the slid- 120 125 able reception of a metal column member having 130

the physical characteristics of the usual standard coupler adapted to engage the draft gear in said first frame, said guide means being in the form of spaced pairs of channel members of different sizes adapted to conform to the dimensions of said column member.

6. In a testing apparatus, the combination with a main frame comprising spaced side members; means for rigidly connecting said members, including a detachable strap; abutment elements at the opposite ends of each of said members, said abutment elements corresponding to the front and rear stop lugs of a railway draft rigging, the abutment elements at one end of said side elements being displaceable; locking means for said displaceable abutment elements; a second frame detachably connected to said first frame, said second frame comprising side members forming continuations of the side members of said first frame and cut out to permit operation of said displaceable abutment elements; spaced means rigidly connecting the side members of said second frame; and spaced guiding elements adapted for the slidable reception of a member corresponding in dimensions to the usual standard coupler to permit transmission of a blow on said coupler to said draft gear.
7. In a testing apparatus, the combination with a main frame comprising spaced side members; means for rigidly connecting said members, including a detachable strap; abutment elements at the opposite ends of each of said members, said abutment elements corresponding to the front and rear stop lugs of a railway draft rigging, the abutment elements at one end of said side elements being displaceable; locking means for said displaceable abutment elements; a second frame detachably connected to said first frame, said second frame comprising side members forming continuations of the side members of said first frame and cut out to permit operation of said displaceable abutment elements; spaced means rigidly connecting the side members of said second frame; and spaced guiding elements adapted for the slidable reception of a column member corresponding in dimensions to a standard coupler to permit transmission of a blow on said column member to said draft gear, said guide elements being in the form of spaced pairs of oppositely disposed channel members, said pairs of channel members being of sizes proportionate to the conformation of a standard coupler.

In witness that I claim the foregoing I have hereunto subscribed my name this 27th day of April 1927.

60 ARNOLD E. DENTLER.
